UNITED STATES PATENT OFFICE.

ERNEST J. SIPES, OF FALKNER, MISSISSIPPI.

DESIGN FOR A BREASTPIN.

Application filed February 26, 1926. Serial No. 16,688. Term of patent 7 years.

To all whom it may concern:

Be it known that I, ERNEST J. SIPES, a citizen of the United States, residing at Falkner, in the county of Tippah and State of Mississippi, have invented a new, original, and ornamental Design for Breastpin, of which the following is a specification, reference being had to the accompanying

drawing, forming part thereof, in which—

Figure 1 is a face view of a breast pin, and Figure 2 is an elevational view of my design for a breast pin.

What I claim is:

The ornamental design for a breast pin as shown.

ERNEST J. SIPES.
